UNITED STATES PATENT OFFICE.

ROY GRIFFITH, OF MELROSE, MASSACHUSETTS.

DETACHABLE AUXILIARY COVER FOR BOOKLETS.

1,191,961.

Specification of Letters Patent. Patented July 25, 1916.

Application filed June 21, 1915. Serial No. 35,454.

To all whom it may concern:

Be it known that I, ROY GRIFFITH, a citizen of the United States, residing at Melrose, in the county of Middlesex and State 5 of Massachusetts, have invented a new and useful Detachable Auxiliary Cover for Booklets, of which the following is a specification.

Books or booklets, in mailing, have hitherto been commonly inserted into envelops. This frequently requires making envelops to order, incurring delay and needless cost. The books or booklets must be put into the envelops, which involves time and labor.

15 My invention aims to eliminate the need of putting books and booklets into separate envelops for mailing, and purposes to provide a mailing cover which both effectually safeguards the books or booklet in mailing, and also can be easily removed in such manner as to leave the book or booklet intact.

Another important object of my invention is to provide a mailing cover which may also be used as a book cover protector. The 25 cover for the booklet may also be used to protect the booklet itself. After the booklet is sent through the mails and received the cover may be used to protect the booklet or pamphlet until the cover becomes soiled.

30 It may then be removed to present a clean booklet.

The above and other objects and advantages of my improvement will fully appear from the following description taken 35 in connection with the accompanying drawings and be explicitly defined in the appended claim.

Figure 1 is a view showing a booklet and the cover attached thereto. Fig. 2 is a perspective view of a booklet embodying my 40 cover. Fig. 3 is a view showing the manner in which the cover is removed from the book or pamphlet after it has been sent through the mails.

45 On the drawing, the booklet is denoted by numeral 5 having leaves 6 and cover 7. The cover 7 is divided into three sections 8, 9 and 10. In section 10, there is a slit 11 into which the tapered or beveled edge 12 of section 8 is adapted to be inserted. The

cover 7 is connected to booklet 5 by means of staples 13.

Instead of a separate envelop, I employ a sheet of paper, cut to fold and protect the complete book or booklet, but fastened to it 55 when it is bound. The cover is fastened to the book or booklet by the lining of the book or booklet itself, whether that lining be by stapling, sewing, or tying,—that is, the binding that extends through the leaves 60 of the book for retaining the same together, is also extended through the cover to retain the same in position on the book.

The cover is easily removed by tearing it from the binding. This leaves the book or 65 booklet complete, still bound, in its own cover.

When it is desired to mail a book having my improved cover thereon, the ends of the cover are extended slightly past the longitudinal free edges of the book and then secured together.

I am aware that prior to my invention a similar mailing device has been used for certain forms of printed matter, though 75 none, to the best of my knowledge and belief, with the purpose of removing the mailing cover; or on a complete book or booklet comprising its own cover; or on a book or booklet intended to be left complete with its 80 own cover, after the removal of the mailing cover.

The broad idea of the process of fastening a mailing cabinet to printed matter in general is not claimed but I desire to claim 85 the following, understanding of course that changes in the details of construction may be resorted to without departing from the spirit of my invention.

I claim:

A combined book cover protector and envelop consisting of a sheet divided into three connected parts arranged in horizontal alignment, one of said parts being smaller than either of the other two and said part 95 having its sides beveled, another of said parts, the one not adjacent to the aforementioned part, having a slit therein into which the first named part with the beveled sides is adapted to be inserted to secure the 100

otherwise free ends together, in combination with a substantially flat booklet having a cover and a plurality of leaves, the combined protector and envelop and said booklet being bound together during the process of binding by means of staples, said combined protector and envelop being of substantially the same width as said booklet whereby the protector

and envelop protects said booklet when the ends of the combined protector and envelop are connected together.

ROY GRIFFITH.
